UNITED STATES PATENT OFFICE.

CLIFTON D. PETTIS, OF CHICAGO, ILLINOIS.

DESIGN FOR A CARLINE.

SPECIFICATION forming part of Design No. 35,003, dated August 27, 1901.

Application filed March 11, 1901. Serial No. 50,767. Term of patent 14 years.

To all whom it may concern:

Be it known that I, CLIFTON D. PETTIS, a citizen of the United States, residing at Chicago, in the county of Cook and State of Illinois, have invented and produced a new and original Design for Carlines, of which the following is a specification.

In the accompanying drawings, which are made a part of this specification, Figure 1 is a perspective view of a carline embodying the new design. Fig. 2 is an end elevation thereof. Fig. 3 is a transverse section thereof, and Fig. 4 is a longitudinal section of a portion thereof on the line 4 4, Figs. 2 and 3.

The essential features of the new design reside in a carline having at its extremities short parallel tongues C, presented downward, and having an intermediate portion corresponding in cross-sectional shape with

a channel-iron of commercial form having 20 its flanges presented upward or away from said tongues, the web A and marginal flanges B of said intermediate portion being bent or deflected upward or away from a straight line drawn from one of said depending tongues 25 to the other, said marginal flanges being continuous and of the same length as the web and said tongues being without marginal flanges.

What I claim as new, and desire to secure 30 by Letters Patent, is—

The design for a carline substantially as herein shown and described.

CLIFTON D. PETTIS.
